CONTROL MECHANISM FOR TYPE CASTING AND COMPOSING MACHINES.

1,042,382.

Specification of Letters Patent.

Patented Oct. 29, 1912.

Application filed February 3, 1911. Serial No. 606,400.

To all whom it may concern:

Be it known that we, JOHN SELLERS BANCROFT and MAURITZ C. INDAHL, of Philadelphia, in the county of Philadelphia, State of Pennsylvania, have invented a certain new and useful Improvement in Control Mechanism for Type Casting and Composing Machines; and we do hereby declare the following to be a full, clear, and exact description of the same, reference being had to the accompanying drawings, forming a part of this specification, and to the figures and letters of reference marked thereon.

This invention relates to the class of type casting and composing machines in which a perforated record strip or pattern is employed to govern the action of the several coordinate mechanisms, and it has for its principal object the suppression by the casting machine of matter registered in the record strip but which it is not desired to produce in type.

The record strip or pattern is composed on a special machine and contains a succession of signals, in the form of perforations, designating characters, points, spaces, etc., arranged in the order of composition and separated into sections by justification signals representing the justification fraction to be applied to the spaces of the preceding line or integral fraction thereof. This justification signal is usually compounded of two individual signals occurring in sequence and each containing both a designating and an admeasuring component, the former operating in the casting machine to designate the particular adjusting mechanism to which the indicated admeasurement is to be applied. The record strip or pattern is delivered to the casting machine in the reverse order of its composition so that the justification signal, now preceding the associated line signals, sets the justification mechanism in advance of the production of the type for the line or section thereof with which it is associated. In addition to the setting of the justification devices the justification signal also controls the galley and pump mechanisms, operating on the first to start it in action, so that the previously designated and composed line will be transferred to the

galley, and operating upon the second to temporarily suspend the action of the pump, so that no metal will be injected into the mold or type be cast while the justification adjustments are being performed.

To provide for sectional line justification, as for tabular matter, a distinction is made between the sectional line justification signal and the final or full line justification signal, and the galley control devices of the casting machine are rendered responsive to the full line signal only, while the pump control devices are responsive to both.

The sectional line justification signal consists, as before stated, of consecutive but different designating perforations each associated with the appropriate dimensioning perforation; while the full line justification signal as well as the last sectional justification signal are compounded of the two designating perforations and an associated admeasuring perforation pertaining to one of said designating perforations, followed, in the casting machine, by a single designating perforation and associated dimensioning perforation. In composing the record strip the double designating perforation signal is formed last while in the casting machine it is presented first for each line.

In the casting machine the pump suspending mechanism is responsive to either of two members controlled by the designating perforations, while the galley starting mechanism is responsive alone to the concurrent action of both of said members, hence the presentation of either component of the sectional line justification signal will cut out the pump without starting the galley—(thus permitting successive line sections to be separately justified and assembled in line), whereas the first component of the full line signal with its two designating perforations will both cut out the pump action and start the galley mechanism to dispose of the preceding line.

It sometimes happens that when composing the record strip, the operator makes a mistake or for other reasons desires to suppress the whole or a portion of a composed line. This he may do either by stopping composition before the line is completed or proceeding to complete the line with odd or

misplaced characters or spaces (for identification) and terminating with a full line justification signal. In either case the line will be composed by the casting machine, necessitating subsequent inspection and removal, and, in the first case, the resulting short line will automatically stop the casting machine. The delays and interruptions thus occasioned not only correspondingly diminish the producing capacity of the casting machine, but afford opportunity for subsequent delays should the condemned matter not be immediately discovered and removed before proofs are taken, all of which is avoided by the present invention wherein and whereby the components of the full line justification signal are rendered operative to suspend the production of the type designated by succeeding line character signals and until the presentation of a normal justification signal, thereby placing the suppression of the condemned matter under the direct control of the operator at the record strip composing machine and insuring its suppression without further attention upon the part of the casting machine operator, proof reader, or corrector.

In the accompanying drawings illustrating a preferred form of embodiment of said invention: Figure 1 is a perspective view of a portion of a type casting and composing machine with the improvement incorporated therein. Fig. 2 is an end view and Fig. 3 a partial side elevation of the devices shown in Fig. 1. Fig. 4 is a top plan view partly in section of the cross head and attachments controlling the pump and galley mechanisms. Fig. 5 is a diagrammatic view of portions of a record strip or controller illustrating sectional and full line justification signals.

The same numerals designate like parts in the several figures.

The invention is herein shown as applied to the type casting and composing machine of Patent No. 625,998, dated May 30, 1899, with the improvements of Patent No. 700,330, dated May 20, 1902, applied thereto; but inasmuch as the improvements have immediate relation to the pump and galley tripping devices, only such parts of the complete organization as are necessary to a full understanding of the subject matter have been illustrated, reference being had to the aforesaid patents for a more detailed description and illustration of the completely organized machine.

In the present instance the members responding to the designating components A, B, of the justification signal are represented by levers 1, 2, forming, in this instance, part of the justification adjusting mechanism, each of said levers operating to elevate one of the two justification wedges into the path of the positioning devices con-

trolled by the admeasuring components C of said signal. The admeasuring component C referred to determines the position of, hence the measurement effected by, the justification wedge with whose designating component A or B it is at the time associated.

In the illustration the galley starting mechanism is represented by a trip 3 and the pump arresting devices by a tripping member or abutment 4, the latter movable into the path of a latch 5 normally connecting the driving and driven members 6 and 7 of the pump actuating devices, to withdraw said latch and thereby disconnect said driving and driven members. Tripping member 4 is attached to a longitudinally movable rod 8 and is held normally removed from the path of the tail of latch 5 by a spring 9 coupled with said rod.

The mechanism for transmitting motion from the designating members or levers 1, 2, to the galley trip and pump arresting devices includes a longitudinally movable shaft 10 in line with trip 3 and to the head 11 carried by said shaft is pivoted an equalizing bar or lever 12 each arm whereof stands opposite and in position to be engaged by one of the designating members 1, 2.

Motion is transmitted from shaft 10 to rod 8 through a pendent link 13 engaging said rod and provided with a pin 14 opposite arm 15 of head 11. Owing to the intermediate, pivoting of lever 12 the motion communicated to shaft 10 by the movement of either lever, 1, 2, will be less in degree than that of the actuating lever, while the motion produced by the engagement of both levers 1, 2, acting in unison will be equal to one half the sum of the movements of the two levers.

The several parts of the transmitting devices are so constructed, disposed and arranged that the movement of shaft 10 derived from either lever 1, 2, acting alone, will be insufficient to throw galley trip 3 while sufficient in extent to cause the engagement of the pump-latch tripping member 4, hence the sectional line justification signal with its single designating member A or B for each component is inoperative so far as the galley starting devices are concerned. When, however, the component of the full line justification signal containing the two designating perforations A, B, is presented, thereby bringing both designating members 1, 2, simultaneously into action, the extended movement communicated to shaft 10 will be sufficient in extent to engage and actuate the galley trip 3 in addition to the pump-latch tripping member 4, thereby setting in action the galley mechanism for the removal of the previously composed and justified line.

The mechanism thus far described does not differ in any material respect from that

disclosed in Patent No. 700,330, and the new function is imposed thereon or incorporated therein by the addition of a locking means or latch suitable for retaining the transmitting devices in the intermediate position to which they are advanced by one designating signal, and responsive to the other justification signal (in the casting machine) to release said latch, thereby preventing the formation of type in response to intermediate signals representing matter which it is desired shall be suppressed. To these ends there is mounted upon the arm 15 of head 11 a latch 20 with its active end 21 in position to engage a shoulder 22 on the frame, and with its tail 23 projecting in front of lever 12 opposite designating member or lever 1. Latch 20 is provided with an advancing spring 24, and is held normally from engagement with shoulder 22 as by the contact of its tail piece 23 with lever 12.

As thus arranged the engagement of latch 20 to lock the pump out of action is placed under the direct control of designating lever 2, when acting alone, while its release is placed under the control of designating lever 1, acting alone or in conjunction with lever 2. Thus when lever 2 is operated the advance of head 11 resulting therefrom withdraws the tail of latch 20 from contact with lever 12, permitting said latch to advance into position to engage shoulder 22 at or near the beginning of the return motion of head 11, thereby locking out the pump action. When, however, lever 1 is operated the arm of lever 12 engaged thereby and contacting with latch 20 advances more rapidly than does the head 11 supporting said latch, thereby not alone preventing an engaging movement of the latch but effecting a slight retraction of the latter. If both levers 1, 2, advance in unison, latch 20 is maintained in retracted position by its engagement with lever 12 whose position relatively to head 11 remains unchanged.

It is obvious, therefore, that when head 11 is held by latch 20 in the intermediate or lock out position to which it has been previously advanced by lever 2 acting alone in response to its designating signal perforation B, it can be released and the head and connected parts returned to initial position by the subsequent advance of lever 1 either alone or in connection with lever 2.

The record strip or pattern for use in connection with the improved control mechanism does not differ in any respect from that heretofore in use so far as matter to be composed in the casting machine is concerned, save that it is required that the component of the justification signal immediately succeeding the matter as composed in the record strip shall contain the designating perforation A followed by the component con-

taining designating perforation B, so that when fed to the casting machine in the reverse order designating lever 1 will follow designating lever 2, to insure the release of latch 20 and the return of head 11 to the normal operating position before the line signals are presented.

When it is desired to cancel the whole or a portion of a line or justifiable section thereof already composed in the record strip said line or section is terminated by a signal containing designating perforation B and composition is continued as before.

As the record strip is fed to the casting machine perforation B will be presented in advance of the series of signals representing the canceled matter, while the latter will be followed by the justification signal pertaining to the next line or justifiable section, said signal comprising two components of which the first, in the order of presentation, contains, for full line justification, designating perforations A and B, and for sectional line justification B, while the second component of said justification signal contains 90 designating perforation A alone.

Upon the presentation of the perforation B, designating lever 2 will be advanced to effect the engagement of latch 20, thereby locking out the pump mechanism and preventing the formation of type as the signals representing the canceled matter are successively presented. When however the first component of the full line signal or the second component of the sectional line justification signal is presented, thereby bringing into action designating lever 1, the advance of head 11 effected thereby will retract latch 20 and restore the pump mechanism to active position, so that upon the presentation of 105 succeeding character or space signals, metal will be injected into the mold and the designated type be produced and assembled in line and transferred to the galley as heretofore.

Having thus described our invention, what we claim as new is:—

1. A control mechanism for type casting machines, including, in combination, the following elements, to wit; two designating members; pump arresting means; galley starting means, transmitting devices intermediate said designating members and said pump arresting and galley starting means adapted to effect action of the pump arresting means through the movement of a single designating member and to effect action of the galley starting means through the further movement derived from both designating members acting together; and a locking means for retaining the pump arresting means in the operative position to which they are brought by a single designating member, said locking means being controlled by the associated designating member to prevent 130

engagement when the latter is actuated either alone or in company with the other designating member.

2. A control mechanism for type casting machines provided with a galley trip, a movable pump arresting member, transmitting devices for said trip and member including a pivoted equalizing bar, and two signal-controlled designating members arranged to act 10 separately and conjointly upon said equalizing bar to actuate the pump arresting member by the movement of either one of said designating members and said pump arresting member together with the galley trip by 15 the further motion derived from both designating members when acting together, and in combination therewith a latch supported to move in unison with said equalizing bar and controlled as to engagement by the designating member associated with one arm of 20 the equalizing bar.

3. A control mechanism for pattern governed type casting and composing machines including, in combination, the following elements, to wit; pattern controlled designating members; pump arresting means; transmitting devices through which motions of the designating members are conveyed to the pump arresting means; a latch controlled by one of said designating members acting 25 to prevent the return or release of the pump arresting devices, and means controlled by the two designating members acting in conjunction for releasing said latch and restoring the action of the pump mechanism. 30 35
